ERASER

Edward A. Clavey, Park Ridge, Ill., assignor to
E. W. A. Rowles Co., Chicago, Ill., a corporation
of Illinois.

Application October 17, 1932. Serial No. 638,158

8 Claims. (Cl. 15—223)

This invention relates to certain new and useful improvements in a noiseless eraser made entirely of non-resonant material, and so constructed as to afford a maximum of wearing and 5 dust-removing qualities and at the same time be capable of economical and rapid manufacture.

The invention relates to certain improvements on the type of eraser disclosed in the patent to Dann No. 817,838, granted April 17, 1906. In this 10 type of eraser a plurality of strips of felt or similar erasing material are positioned in mutual contact and at right angles to a back-piece or supporting member so that the free edge portions of the assembled strips form the erasing 15 surface. The other edge portions of the strips are attached to the back-piece in such a manner that the strips are held firmly in yielding contact with one another. The present improvement relates more particularly to a novel back-piece 20 formed of a slab of relatively soft and light fibrous material which is reinforced by a fabric covering wrapped around the slab and glued thereto. The felt erasing strips are secured to the back-piece by lines of stitching which pass through both the 25 fibrous slab and the fabric covering in the novel manner hereinafter set forth.

The principal object of this invention is to provide an improved eraser of the type briefly described hereinabove and disclosed more in detail 30 in the specifications which follow.

Another object is to provide an improved back-piece for an eraser.

Other objects and advantages of this invention will be more apparent from the following detailed description of one approved form of eraser 35 constructed according to the principles of this invention.

In the accompanying drawing:

Fig. 1 is a perspective view of the complete 40 eraser.

Fig. 2 is a perspective view showing an initial step in the construction of the eraser.

Fig. 3 is a perspective view showing a succeeding 45 step in the assembly of the eraser parts.

Fig. 4 is a partial perspective view of the improved back-piece.

Fig. 5 is a transverse section through the assembled eraser.

The eraser comprises a relatively stiff back-piece or handle A and a plurality of strips of felt or similar erasing material indicated generally at B, these strips being attached to and supported by the back-piece A. The improved back-piece A comprises an inner slab 1 of a rather soft and light fibrous material, for example a wood fiber product such as is known commercially as "quarter-board". This product is light, cheap, and non-resonant, but does not in itself possess the requisite strength and wearing qualities to support the erasing strips B. The slab 1

is covered, except at the ends, by a sheet 2 of relatively tough fabric, preferably canvas, which is wrapped tightly about the slab and glued securely thereto. Preferably the meeting portions 3 and 4 of the fabric sheet 2 are overlapped and glued upon one another along one flat face of the slab, preferably the bottom thereof. The overlapped portions need not cover the entire flat face of the slab, but these overlapped portions are preferably of sufficient extent so that at least two of the lines of stitching hereinafter referred to will pass through the double thickness of canvas on the bottom of the slab.

In the example here shown the erasing portion B comprises fixed strips 5, 6, 7, 8, 9 and 10 of felt or similar material, which strips are arranged in contact with one another and at substantial right angles to the back-piece A so that the free lower edge portions of the strips lie in substantially the same plane and form the erasing surface. One of the outer strips, for example strip 5, is laid flatwise against the lower surface of the back-piece A (which is inverted as shown in Fig. 2) with the outer edge 12 of the strip substantially aligned with the outer edge portion 13 of the back-piece. The strip is then secured to the back-piece by a line of stitching 11 extending longitudinally of the eraser and parallel to the edge portions 12 and 13 and extending entirely through the strip 5, from the outer face thereof, and through both the slab 1 and fabric covering 2 of the back-piece. The other outer strip 10 is now secured to the opposite edge portion of the back-piece in a similar manner by a similar line of stitching 14.

The outermost strips 5 and 10 are now bent up as indicated in Fig. 3 and the intermediate strips 6 to 9 are mounted on the back-piece between these outer strips. These inner strips are formed in pairs, a sheet of felt of substantially twice the width of one of the strips 5 or 10 being folded longitudinally upon itself to form a pair of adjacent strips such as 6 and 7. This pair of strips is secured to the back-piece by a line of stitching 15 passing through the back-piece and the folded portion of the felt member between the adjacent strips of the pair. While two pairs of intermediate strips 6, 7, and 8, 9 are here shown, it will be apparent that three or more pairs of such intermediate strips could be used and the width of the eraser increased accordingly.

It will be apparent that the outwardly folded outer strips 5 and 10 exert an inward pressure on the intermediate strips tending to hold the assembly firmly together, and the mutual engagement of the assembled strips tends to prevent flattening out of the free rubbing edge portions thereof. At the same time a limited freedom of movement is permitted between the strips so that

a resilient and effective rubbing surface is provided.

The canvas covering 2 gives the requisite strength and rigidity to the relatively soft and fragile fibrous slab 1 which forms the main body portion of the back-piece. The lines of stitching pass completely through the back-piece so that the fabric covering will prevent the stitches from pulling through the relatively soft slab 1. Preferably at least two of the lines of stitching 11, 14 or 15 pass through the overlapped portions 3 and 4 of the fabric covering. This effectively prevents splitting of the back-piece when subjected to the bending stresses encountered when in use. A back-piece constructed in this manner is very light and noiseless, and may be quite cheaply and rapidly constructed. At the same time it has the requisite strength and stiffness to firmly and permanently support the felt erasing strips, and provides a very satisfactory handle having a good gripping surface.

While the canvas covering 2 has been designed for the primary purpose of adding the requisite strength and stiffness to a fibrous slab 1 which in itself is too fragile for successful use without the canvas covering, it will be understood that the same covering will be useful to enhance the strength of a stronger fibrous slab, for example, a slab of felt, as heretofore known and used in this type of eraser. Although felt has been used as a back-piece with some success, without the fabric covering, the felt slab is weakened by the lines of stitching and will sometimes break along these lines, and the canvas covering will reinforce and stiffen such a felt slab in the manner hereinabove set forth.

A plurality of these erasers may be simultaneously formed by first constructing a long strip in the manner hereinabove described and then cutting this strip into suitable lengths to form the finished erasers.

It will be apparent that this eraser is entirely free from any substance which can either injure the blackboard or be capable of making any objectionable sound.

The felt strips might be attached to the back-piece in other manners than that herein disclosed, but the form here shown is preferred since the lines of stitching add strength and rigidity to the back-piece and securely hold all of the parts in assembled relation.

I claim:

1. An eraser comprising a non-resonant back-piece, and a plurality of strips of resilient erasing material positioned in contact with one another and secured to the lower face of the back-piece by lines of stitching, the back-piece comprising a slab of fibrous material and a fabric covering wrapped around the slab and glued thereto, the lines of stitching passing through both the fibrous material and the fabric.

2. An eraser comprising a non-resonant back-piece, and a plurality of strips of resilient erasing material positioned in contact with one another and secured to the lower face of the back-piece by lines of stitching, the back-piece comprising a slab of fibrous material and a sheet of fabric wrapped around the slab and glued thereto, the meeting portions of the sheet being overlapped upon one flat face of the slab, the lines of stitching passing through both the fibrous material and the fabric covering, and some of the lines of

stitching passing through the overlapped portions of the fabric.

3. An eraser comprising a non-resonant back-piece, and a plurality of strips of resilient erasing material positioned in contact with one another and secured to the lower face of the back-piece by lines of stitching, the back-piece comprising a slab of fibrous material and a sheet of fabric wrapped around the slab and glued thereto, the meeting portions of the sheet being overlapped upon the lower flat face of the slab, the lines of stitching passing through both the fibrous material and the fabric covering, and some of the lines of stitching passing through the overlapped portions of the fabric.

4. An eraser comprising a non-resonant back-piece formed of a slab of fibrous material and a sheet of fabric wrapped therearound and glued thereto with the meeting portions of the sheet overlapped upon one flat face of the slab, and a plurality of strips of felt positioned closely adjacent one another so as to provide a mutually elastic support, the lower erasing edge portions of the strips projecting at substantial right angles from the lower face of the back-piece, the upper edge portions of the outermost strips being sewed from the outer sides of the strips through the back-piece, the strips being then folded outwardly, and the inner strips being formed in pairs each pair being folded from a single piece of felt and the pair being sewed to the back-piece by a line of stitching passing through the folded portion between the strips of the pair, all of the lines of stitching passing through both the fibrous slab and the fabric covering, and some of the lines of stitching passing through the overlapped portions of the fabric.

5. An eraser comprising a non-resonant back-piece formed of a slab of soft fibrous material and a reinforcing sheet of fabric wrapped around the slab and glued thereto with the meeting portions of the sheet overlapped upon one flat face of the slab, and a plurality of strips of felt positioned closely adjacent one another so as to provide a mutually elastic support with the lower erasing edge portions of the strips projecting at substantial right angles from the lower face of the back-piece and the upper edge portions of the strips secured to the back-piece.

6. An eraser comprising a non-resonant back-piece formed of a slab of soft fibrous material and a reinforcing covering of fabric glued thereto, and a plurality of strips of felt positioned closely adjacent one another so as to provide a mutually elastic support with the lower erasing edge portions of the strips projecting at substantial right angles from the lower face of the back-piece and the upper edge portions of the strips secured to the back-piece.

7. A back-piece for an eraser comprising a slab of fibrous material and a fabric covering wrapped tightly around the slab and glued thereto, the meeting portions of the fabric covering being overlapped and glued upon one another along one flat face of the slab.

8. A back-piece for an eraser comprising a slab of wood fibre and a canvas covering wrapped tightly around the slab and glued thereto, the meeting portions of the canvas covering being overlapped and glued upon one another along one flat face of the slab.

EDWARD A. CLAVEY.
